UNITED STATES PATENT OFFICE.

BERNIE C. KRIDLIER, OF CHICAGO, ILLINOIS, ASSIGNOR TO CAMPBELL WIRE SPECIALTY WORKS, OF SOUTH BEND, INDIANA, A CORPORATION OF INDIANA.

ROOFING MATERIAL.

Application filed August 21, 1924. Serial No. 733,279.

To all whom it may concern:

Be it known that I, BERNIE C. KRIDLIER, a citizen of the United States, and a resident of Chicago, in the county of Cook and State of Illinois, have invented certain new and useful Improvements in Roofing Material, of which the following is a specification.

Among the principal objects which the present invention has in view are: to avoid the curling or upturning of the free edge of shingles or similar members constructed from flexible material; to facilitate the operation of covering a roof; to economize on the material manufactured from sheets of standard size; and to avoid the necessity of locating proper points of disposition of the fasteners for said shingles.

Drawings.

29 Figure 1 is an isometric perspective view of a portion of a roof, the same being shown as in the act of receiving a covering, constructed and arranged in accordance with the present invention.

25 Figure 2 is a cross section of the same on enlarged scale, the section being taken as on the line 2—2 in Figure 1.

Figure 3 is a section of a fragment of the roof on an increased scale, the section being taken as on the line 3—3 in Figure 1.

Figure 4 is a top side view of a sheet of roofing material, one section being severed from the body of the material and the remainder of the material being marked for severance.

Description.

As seen best in Figure 4 of the drawings, the shingle member constructed in accordance with the present invention, consists of a roofing section 9 which is severed from the body of a sheet of roofing material indicated by the numeral 10. The lines of severance shown by the dotted lines 11 in said figure 45 of the drawings are stepped in the manner shown, the indentation or horizontal lines 12 being equal to one half the exposed width of shingles of the usual construction.

Either simultaneous with the severing of the section 9 or subsequent thereto, each section is provided with a series of perforations 13 provided particularly to receive the shank 14 of a clip 15. The clip 15 has a hook-end 16 which in practice stands upright or perpendicular to the plane of the

roof, until a shingle section is laid against it. It is then overturned in the manner disclosed in Figure 3 of the drawings to thereafter hold the shingle section firmly in position.

As seen best in Figure 1, the hook-ends 16 rest at the inner corner of the lines of severance of the various shingle sections. The sections 9 are arranged in simulation of a multiplicity of shingles, and the sections 17 cover a roof space equal to a number of shingles, though the sections are placed in position on the roof with almost the celerity and rapidity that the single shingle of usual construction is placed.

As will be seen in Figure 1 of the drawings, the exposed ends or edges formed by the severance are held firmly in position by the clips 14 which are disposed at every one of the inner angles of the line of severance. 75 Also it will be observed that the exposed portions of each section presents a triangular surface to the weather which offers the greatest resistance to any effort on the part of the wind to upturn the said exposed portions.

To more nearly imitate the appearance of the usual shingle, the sections 9 have imprinted therein preferably by scoring, a series of lines 17 which are extensions of the 85 horizontal edges 12. The lines 17 register with the edges 12 of the netherposed and superposed sections and carry the appearance in the completed roof of full exposed square shingle ends.

Claims.

1. Roofing material comprising a plurality of roofing sections, said sections having shingle-like exposed edges cut in inner angles and disposed in inclined relation to the horizontal plane of the roof, said sections having perforations for receiving fastening members, said perforations being disposed to coincide with the inner angles of the exposed edges of the roofing section to be super-imposed upon said perforated section.

2. Roofing material comprising a plurality of roofing sections, each of said sections having its top and bottom edges disposed in 105 parallel relation and having its opposite side edges cut in step formation forming inner angles in one side edge, said sections having perforations for receiving fastening members disposed adjacent the inner angles of 110

2
the exposed edges of roofing sections to be side edges cut in stepped relation with one 10
superimposed thereon, and fastening members securing each of said sections in each
of the inner angles in the weather side edges thereof.

3. Roofing material comprising a plurality of superimposed roofing sections each of 15
which is formed with straight parallel top and bottom edges, said sections having their
each of the inner angles formed therein.

BERNIE C. KRIDLER.
